EARMUFFS OR SIMILAR ARTICLE

Alex S. Tremulis, Ann Arbor, Mich., assignor to Peter S. Pagratis and Ralph W. Olsen, doing business as Commodities Sales Co. of America, Chicago, Ill., a copartnership

Application December 24, 1954, Serial No. 33,676

Term of patent 14 years

(Cl. D3—2)

To all whom it may concern:

Be it known that I, Alex S. Tremulis, a citizen of the United States and a resident of the city of Ann Arbor, in the county of Washtenaw, and State of Michigan, have invented a new, original, and ornamental Design for Earmuffs or Similar Article, of which the following is a specification, reference being had to the accompanying drawing, forming a part thereof.

On the drawing:

I claim:

The ornamental design for earmuffs or similar article, as shown.
